UNITED STATES PATENT OFFICE.

WILLIAM H. CLARK, OF CLEVELAND, OHIO.

SCREW-PROPELLER

1,007,183.

Specification of Letters Patent. Patented Oct. 31, 1911.

Application filed May 20, 1910. Serial No. 562,501.

To all whom it may concern:

Be it known that I, WILLIAM H. CLARK, citizen of the United States, residing at Cleveland, in the county of Cuyahoga and State of Ohio, have invented certain new and useful Improvements in Screw-Propellers, of which the following is a specification.

This invention relates to screw propellers of that type having adjustable blades, and the propeller is particularly adapted and intended for use on a flying machine; for aerial propulsion, but the principles thereof are capable of application to propellers used for marine propulsion.

The object of the invention is to provide improved means for adjusting the blades and controlling the angle thereof, so as to vary the driving power according to local conditions. The propeller may be used for direct propulsion in the line of flight, or it may be used for lifting purposes, when applied to flying machines.

An embodiment of the invention is illustrated in the accompanying drawings in which—

Figure 1 is a top or end view of the propeller. Fig. 2 is a side elevation thereof, partly broken away. Figs. 3, 4, 5 and 6 are details in plan and section of various parts to be hereinafter particularly described. Fig. 7 is an elevation of a modification.

Referring specifically to the drawings, A indicates a driving shaft which turns in a bearing in a casting B and is geared by bevel wheels C to the propeller shaft D one end of which is stepped in a bearing in the angle casting B which is mounted on a member H of the frame. The other end of the shaft D is keyed to a hub or casting E having four angular arms as shown, each arm consisting of a radial member extending outwardly from the center and connected by an elbow to an outer member at right angles thereto, these arms being arranged symmetrically around the center, the radial member being indicated at 6 and the outer member at 7, and all the arms being in the same plane. At the outer end of each radial member 6 is a guide pin F, and projecting outwardly from the end of the outer member 7 is a pivot rod G, which is rigid with the arm. The propeller blades S are mounted to turn on the rods G, by clips T, and said rods serve to support a part of the

thrust on the blades, and the blades may be adjusted on said rods as axes to vary the inclination or angle of the blades with respect to the plane of the wheel. A bracket J is fastened to another part of the frame 60 H, and said bracket supports a bent lever K which is pivoted at its elbow to the bracket and is connected at its outer end to an operating rod R. The other arm of the lever has a pin and slot connection at 8 to 65 a collar L which works in a groove in a sleeve M fast on one end of a tube N which incloses the shaft D. At its other end the tube is fastened to a casting O which has four radial arms projecting from the center 70 thereof, and each arm has at the outer end an upright part which extends parallel to the shaft and is slotted as at P, and these slots receive the guide pins F so that the castings E and O are locked against relative 75 rotation, but the casting O may be moved lengthwise on the shaft. At the elbow of each arm O is a rod U extending radially, and parallel to the rods G, and the rods U have rollers Q thereon, which fit under 80 guide straps V attached to the blades.

By operation of the rod R and bent lever K the tube N and casting O attached thereto may be moved lengthwise on the propeller shaft, and when this is done the rods U are moved to a position toward or from the rods G, and such movement, by means of the rollers Q and straps V, turns the blades S on the pivot rods G, and so varies the angle of pitch of all the blades. As the head or casting O is moved toward the casting E the blades are turned to decrease the angle thereof with respect to the plane of the wheel, and reversely, opposite motion increases it. Both the rods G and the rods U assist in supporting the thrust or strain on the blades, and the construction provides a very light and convenient mechanism for effecting the result indicated.

Various modifications are possible within the scope of the invention. Thus in the accompanying drawings four blades are illustrated, but the number of blades may be varied as desired, and no limitation in this respect is implied. Furthermore, instead of having the pivot rods of the blades relatively fixed, and the shifting rods relatively movable, the construction may be reversed; that is, the tube N and the rods attached thereto may be relatively fixed, and the 110

shaft shiftable to move the pivot rods toward or from the other rods, as shown in Fig. 7.

Having thus described the invention, what I claim as new, and desire to secure by Letters Patent is:—

1. The combination of a propeller shaft, a hub thereon having outwardly projecting angular arms with guides thereon, blades 10 pivotally attached to the outer ends of said arms, a tubular member surrounding and 15 shiftable along the shaft and engaging the guides to prevent rotation of the member relative to the hub, and connections between 20 said member and the blades to turn the latter on their pivots when the member is shifted along the shaft.

2. The combination of a propeller shaft, a hub fast thereto, pivot rods projecting 20 outwardly from the hub, blades mounted to turn on said rods, a head shiftable along the shaft, guides between the hub and head to

prevent relative rotation thereof, rods projecting from the head, parallel to the pivot rods and connected to the blades, to turn 25 the same on the pivot rods, and means to shift the head along the shaft.

3. The combination of a propeller shaft, a hub fixed thereon and having projecting guide pins, blades pivotally connected to 30 said hub, a head shiftable along the shaft and having arms extending parallel to the shaft, said arms having slots in which the pins are engaged, to prevent relative rotation of the hub and head, and connections 35 between the head and the blades to turn the latter on their pivots when the head is shifted along the shaft.

In testimony whereof, I do affix my signature in presence of two witnesses.

WILLIAM H. CLARK.
